M. M. DILUCHIO,
PILOT FOR GAS BURNERS.
APPLICATION FILED NOV. 3, 1917.

1,272,780.

Patented July 16, 1918.

UNITED STATES PATENT OFFICE.

MICHAEL M. DILUCHIO, OF WILMINGTON, DELAWARE.

PILOT FOR GAS-BURNERS.

1,272,780.

Specification of Letters Patent. Patented July 16, 1918.

Application filed November 3, 1917. Serial No. 200,117.

To all whom it may concern:

Be it known that I, MICHAEL M. DILUCHIO, a citizen of the United States, residing at Wilmington, in the county of New Castle and State of Delaware, have invented certain new and useful Improvements in Pilots for Gas-Burners; and I do hereby declare the following to be a full, clear, and exact description of the invention, such as will enable others skilled in the art to which it appertains to make and use the same.

This invention relates to improvements in pilots for gas burners and has for one of its objects the provision of a device of this character which will prevent the breaking of the mantle when the burner is ignited by the pilot.

Another object of this invention is the provision of the ignited end of the pilot forming an integral structure of the mantle support, so that the mantle will be ignited from the interior instead of from the exterior, thereby obviating the breaking of the mantle caused by the explosion produced by the ignition of the same from the exterior as now customary.

A further object of this invention is the provision of a pilot for gas burners of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts, as will be hereinafter more fully described and claimed.

For a complete understanding of my invention, reference is to be had to the following description, and accompanying drawing, in which:—

Figure 1 is a vertical sectional view of a gas burner illustrating my invention applied thereto.

Fig. 2 is a fragmentary vertical sectional view illustrating the ignited end of the pilot forming an integral structure of the mantle support,

Fig. 3 is a fragmentary vertical sectional view of a coupling used in connection with the supply pipe of the pilot,

Fig. 4 is a modified form of the same,

Fig. 5 is a perspective view of a member

for detachably connecting the supply pipe of the pilot to the mantle support.

Referring in detail to the drawing, the numeral 1 indicates the casing of the gas burner having mounted therein the usual gas supply pipe 2 provided with controlling valves 3 and 4. The other end of the gas supply pipe 2 is enlarged as illustrated at 5 and internally threaded as illustrated at 6 for the purpose of having a mantle support 7 threaded thereto. The mantle support 7 is constructed from, in a molding process, a plastic composition, and has formed thereon a mantle supporting rim 8 for supporting the usual mantle 9 that is constructed from foraminous material. The mantle support 7 when being molded is formed with a vertical passage 10 that terminates in a nipple 11. The nipple 11 forms an integral portion of the mantle support and extends 75 downwardly and inwardly forming the igniting end of the pilot. The vertical passage 10 at its other end terminates in a horizontal branch opening outwardly through the side of the mantle support. A cylindrical member 12 is internally screw threaded and positioned in the horizontal branch of the passage 10 and has formed upon its inner end a plurality of retaining fingers 13 that are embedded within the mantle 85 support 7 when molding the same so as to retain the cylindrical member 12 within the horizontal branch. A pipe 14 is threaded into the cylindrical member and has its other end threaded into an elbow 15. The elbow 90 15 has threaded thereto a gas feed pipe 16 that extends upwardly through the casing and has slidably mounted thereon a sleeve 17. Interposed between the sleeve 17 and the pipe 16 is a packing 18 to establish an air tight connection therebetween, but which will permit the sleeve 17 to be moved or slid upon the pipe 18 when desired. A curved pipe 19 connects with the gas feed pipe 2 at a point adjacent the controlling valve 4 and 95 has its other end disposed within the sleeve 17. A packing 20 is disposed between the pipe 19 and the sleeve to establish an air tight connection but which will permit a sliding movement of the sleeve 17 upon the pipe 19.

If desired, the pipes 18 and 19 may be provided with screw threads as illustrated in Fig. 4, which threads run in opposite directions to be threaded in engagement with a 110

sleeve 21 that is internally threaded in the opposite direction for the purpose of co-operating with the threads upon the pipes 18 and 19 providing means whereby the pipes will be detachably connected together. By having the pipes 18 and 19 detachably connected provides a construction wherein the pipe 14 may be first threaded to the cylindrical member 12 and the elbow 15 then threaded thereon. The pipe 16 may then be threaded to the elbow 15 and connected to the pipe 19 as shown in either of the Figs. 3 or 4.

From the foregoing description taken in connection with the accompanying drawing, it will be noted that the ignited end of the pilot forms an integral structure of the mantle support so that it is disposed within the mantle 9 whereby upon igniting the burner, the gas will be ignited from the interior of the mantle instead of from the exterior of the mantle as now customary upon all well known gas burners. By igniting the mantle from the interior thereof it obviates the danger of breaking the same as, if the mantle is ignited from the exterior the explosion of the gas from the outside of the mantle when becoming ignited will break the same.

While I have shown and described the preferred embodiment of my invention, it will be understood that minor changes in construction, combination, and arrangement

of parts may be made, without departing from the spirit and scope of the invention as claimed.

Having thus described my invention, what I claim is:

1. A pilot for gas burners comprising a mantle support having a passage formed therein, a nipple formed on the support and in communication with the passage, a cylindrical member embedded in the mantle and within the passage, a pipe threaded to said cylindrical member, an elbow threaded to said pipe, a feed pipe threaded to the elbow, a sleeve detachably connected to the feed pipe, and a curved pipe connected to the main gas feed pipe of a gas burner and detachably connected to the sleeve.

2. A gas burner comprising a mantle support having a main centrally located gas passage and an auxiliary passage extending parallel therewith, a nipple formed on the mantle support and in communication with the auxiliary passage, and means supplying gas to the auxiliary passage.

In testimony whereof I affix my signature in presence of two witnesses,

MICHAEL M. DILUCHIO.

Witnesses:

HORACE GREELEY EASTBURN,
BARNET STUCKMAN.
